UNITED STATES PATENT OFFICE.

IVY D. HOWELL, OF BALLSTON SPA, NEW YORK.

CORSET.

1,227,442.

Specification of Letters Patent. Patented May 22, 1917.

Application filed October 29, 1915. Serial No. 58,597.

To all whom it may concern:

Be it known that I, Ivy D. Howell, a citizen of the United States, residing at Ballston Spa, in the county of Saratoga and State of New York, have invented certain new and useful Improvements in Corsets; and I do hereby declare the following to be a full, clear, and exact description of the invention, such as will enable others skilled in the art to which it appertains to make and use the same.

This invention relates to corsets and the primary object of the invention is to provide an attachment for corsets, which is particularly designed for use by stout women, for supporting their abdomen, and which is constructed so that it will gradually reduce the size of the abdomen.

Another object of this invention is to provide an absorbent shield for use in connection with the abdomen supporting structure which is to be positioned between the legs of the wearer and assist in supporting the abdomen as well as absorbing perspiration or other moisture cast off by the wearer, and further to provide a shield as specified which may be easily removed and a dry one attached in lieu of the same, thereby eliminating all discomfort such as the torture of scalding in summer and chafing in winter.

A still further object of the invention is to provide a back shield which is reinforced by stays and is constructed so that it will prevent the clothing from catching between the hips of the wearer when arising from a sitting position, or upon stooping or bending, and to attach an elastic tape to the back shield which is provided for extending about the waist of the wearer.

A still further object of this invention is to provide a corset construction as specified which includes all of the various parts, namely the abdomen engaging and supporting members, the leg pad or shield and the back shield which parts are connected so that they may be easily and quickly disconnected or removed when desired and further to provide a strap which extends through the leg shield and which may be attached to the abdomen engaging and supporting member if it is so desired, eliminating the use of the leg shield.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which:—

Fig. 1 is a view of an ordinary corset showing the improved attachment, attached thereto;

Fig. 2 is a fragmentary view of the corset showing the invention attached and showing the side opposite to that illustrated in Fig. 1;

Fig. 3 is a detail view of the back pad;

Fig. 4 is a section on the line 4—4 of Fig. 1;

Fig. 5 is a section on the line 5—5 of Fig. 1;

Fig. 6 is a section on the line 6—6 of Fig. 1; and

Fig. 7 is a section on the line 7—7 of Fig. 1.

Referring more particularly to the drawings, 1 designates the body of an ordinary corset, which is slightly altered to accommodate the attachment thereto of the abdomen supporter and flesh reducer of this invention.

The corset 1 is provided with a plurality of eyelets 3 through which the laces 4 are inserted which laces attach the abdomen supporting members 5 and 6 to the body of the corset.

The abdomen supporting members 5 and 6, are constructed of soft cloth and have their edges bound as is shown at 7. Each of the members 5 and 6 have upwardly extending projections 8 and 9 formed thereon to which the straps 10 and 11 respectively are attached. The straps 10 and 11 are provided with a plurality of eyes 12 and have rings 13 attached to their free ends. The straps 10 and 11 extend upwardly from the projections 8 and 9 and through slits 14 formed in the corset 1, which positions the upper free ends of the straps on the outer surface of the corset body. Hooks 15 are at-

tached to the outer surface of the corset body above the slits 14 and are provided for extending through the eyelets 12, for holding the straps, and consequently the 5 abdomen supporting members 5 and 6 in various adjusted positions.

The abdomen supporting member 5 is connected to the member 6 by ordinary hook and eye connections 18 and 19. A protecting flap 20 is attached to the member 6 and extends beneath the eyes 19 for preventing the hooks 18 and eyes 19 from irritating the wearer of the device.

Each of the members 5 and 6 has an eye 15 or analogous fastening device 21 attached to its outer surface adjacent its lower inner corner, which is adapted for connection with a hook or fastening means 22. The fastening means 22 is attached to the leg pad 23. The leg pad 23 is preferably formed of soft 20 cloth which has absorbent properties and is substantially circular shaped in plan, but any shape desired may be employed without departing from the spirit of this invention. A strap receiving pocket 24 is formed upon the upper side of the leg pad and extends longitudinally along the center of the same. The strap 25 is attached to one end of the hip pad 26, and is covered with 25 rubber sheeting as is indicated at 26'. The strap 25 has an eye or analogous fastening device 27 attached to its end, which eye or fastening device is provided for coacting with a hook or attaching device attached to 30 the inner surface of the pocket 24, for holding the strap within the pocket and eliminating the liability of the accidental removal of the same therefrom.

Fastening devices 30 are also attached to 40 the free ends of the strap 25 and are adapted for coaction with the attaching members 21, when it is desired to dispense with the leg pad 23. The pocket 24 has fastening means 32 attached to the inner surface of its end 45 remote from the attaching members 21, which fastening means 32 are adapted for coaction with fastening devices 33 carried by the back pad 26.

The back pad 26 is reinforced by trans- 50 versely extending ribs or stays 34. An elastic belt 36 is attached to the upper edge of the back pad 26. The elastic belt 36 is constructed of two detachably connected sections 37 and 38, which are adapted for ex- 55 tending about the waist of the wearer for holding the back pad in proper position. The length of each of the sections 37 and 38 is adjustable in the ordinary manner.

When the improved corset is worn by a 60 person, the back pad is attached in its proper place by passing the elastic straps about the waist of the wearer, after which the abdominal support is adjusted to fit the abdomen of the wearer, by adjustment of the 65 straps 10 and 11. In the use of the abdomi-

nal support, the back pad and leg straps which connect the back pad to the lower edge of the abdominal support, will prevent upward creeping movement of the support and hold it in its proper position.

The corset or garment is first applied like an ordinary corset, and fastened about the wearer, after which the straps 11 are adjusted for adjusting the position of the members 5 and 6 to properly support the 70 abdomen of the wearer. After the abdominal support has been properly adjusted, the leg pad 23 is passed between the legs of the wearer, and the back pad 26 is properly positioned, after which the belt 36, which is 75 constructed of the elastic members 37 and 38, is properly adjusted and fastened about the waist of the wearer which holds the back pad 26 in its proper position and coacts with the back pad and the leg pad in preventing 80 the abdominal supporting members from 85 creeping upwardly.

What is claimed is:—

1. In a corset structure, the combination with a corset, of a pair of abdominal engaging and supporting members detachably carried by the corset, means attached to the upper ends of said abdominal supporting members for adjustably connecting them to the corset, a leg strap connected to the 90 lower edge of said supporting members, a back pad connected to said leg strap, elastic waist encircling members attached to said back pad, said back pad and leg-strap holding the lower edges of said abdominal supporting members against upward creeping movement.

2. In a corset structure, the combination, of a pair of abdominal engaging and supporting members detachably connected to a 105 corset, fastening means carried by the outer vertical marginal edges of said members for connecting the members when the corset is worn, straps connected to said members, means carried by said corset for coaction 110 with said straps for holding the straps and said abdominal engaging members in various adjusted positions, a leg strap connected to the lower edge of said support, a back pad connected to said leg strap, an elastic 115 waist encircling member attached to said back pad, said back pad and leg straps holding the lower edges of said abdominal supporting members against upward creeping movement.

3. The combination with an ordinary corset having a plurality of slits formed therein a short distance below its upper edge, of a pair of abdominal supporting members detachably connected to said corset, straps connected to said abdominal supporting members and extending upwardly through said slits, said straps having their outer ends positioned upon the outer surface of the corset, means carried by the 120 125 130

outer surface of the corset for engaging said straps for holding the straps and said abdominal supporting members in various adjusted positions, a leg strap connected to the lower edge of said support, a back pad connected to said leg strap, and elastic waist encircling members attached to said back pad, said back pad and leg strap holding the lower edges of said abdominal sup-

porting members against upward creeping 10 movement.

In testimony whereof I affix my signature in presence of two witnesses.

IVY D. HOWELL.
